INVENTOR:
CLARENCE WRIGHT

By

Edwin B. H. Tower Jr. ATTY.

UNITED STATES PATENT OFFICE

CLARENCE WRIGHT, OF RACINE, WISCONSIN, ASSIGNOR TO WRIGHT RUBBER PRODUCTS COMPANY, OF RACINE, WISCONSIN, A CORPORATION OF WISCONSIN

PAVING BLOCK

Application filed January 9, 1925, Serial No. 1,422. Renewed March 17, 1930.

This invention relates to paving blocks and pavements.

The paving blocks to which the invention applies in particular have flanges at the bottom thereof for interlocking the blocks.

A pavement formed of such blocks is held in place by fasteners which extend through the flanges of the blocks and are anchored in the foundation.

10 The fasteners hold the pavement against movement under normal conditions but abnormal traffic or excessive strains may cause the pavement to creep.

An object of the invention is to provide a 15 paving block which may be securely fastened in place.

Another object is to provide a paving block capable of holding other paving blocks against movement.

20 Another object is to provide a paving block having a rigid insert therein to distribute strains throughout the block.

Another object is to provide a pavement formed of interlocking blocks and having a 25 part of said blocks provided with reinforcements to enable the same to be securely anchored to the foundation and hold the other blocks against lateral movement.

According to the invention, the block has 30 a reinforcing plate to resist strains and stresses and transfer the same to the fasteners which secure the block to its foundation.

The block is ordinarily incorporated in a pavement in conjunction with other blocks 35 to hold the same against creeping.

A paving block and a pavement embodying the invention are shown in the accompanying drawing in which the views are as follows:

40 Fig. 1 is a plan view of the block.

Fig. 2 is a perspective view thereof.

Fig. 3 is a central longitudinal section.

Fig. 4 is a central longitudinal section showing two blocks interlocked with each 45 other and secured to a foundation.

Fig. 5 is a plan view of a paving formed of individual blocks and having one row thereof provided with reinforcing plates.

The invention is shown embodied in a paving block of the form disclosed in the patent

to Healy, Reissue No. 16,867 of February 7, 1928, but it may also be incorporated in other forms of paving blocks.

This block has a top 1 of rectangular or other suitable shape and a bottom which is 55 provided with flanges 2 projecting from the block and recesses 3 underneath the top.

These flanges and recesses correspond in shape and size and are arranged contiguously or side by side with the edges thereof 60 merging into each other.

The top and bottom have vertical edges and the flanges and recesses have flat tops.

The recesses of one block are adapted to receive the flanges of the adjoining blocks. 65

A reinforcing plate 4 of rigid material, such as metal, is secured to or embedded in the block intermediate the recesses 3 and preferably extends nearly the length of the block.

Openings 5 are provided in the block in 70 alignment with apertures 6 in the plate 4 to receive fasteners 7 for securing the block to a foundation.

The heads 8 of the fasteners 7 are below 75 the surface of the top 1 and the openings 5 may be closed with plugs 9 of the same material as the block.

A pavement formed of interlocking blocks is ordinarily secured to its foundation by 80 nails or other fasteners which are passed through the flanges 2 of the blocks and into the foundation, as disclosed in the Healy Patent Re. 16,867.

The nails or other fasteners prevent the 85 pavement from creeping under ordinary conditions.

Pavements which are subjected to excessive strains and stresses may be prevented from 90 creeping by having blocks embodying the invention incorporated therein and rigidly secured to the foundation.

These blocks are ordinarily arranged across 95 each end of the pavement and may also be placed at intervals between the ends thereof, as shown in Fig. 5.

The thrust of the adjoining blocks is received evenly along the sides of the plate 4 and transferred thereby to the fasteners 7 which hold the blocks against moving.

The invention herein set forth is suscepti- 100

ble of various modifications and adaptations without departing from the scope thereof as hereafter claimed.

The invention is hereby claimed as follows:

- 5 1. A paving or covering block, comprising, a top having a bottom shaped to provide flanges extending beyond said top and complementary recesses extending beneath said top, and a plate arranged within said block to reinforce and strengthen the same and receive means to fasten the block to a foundation.
- 10 2. A paving or covering block, comprising, a top having vertical edges, bottom having vertical edges and shaped to form flat top flanges extending beyond said top and having recesses arranged between said flanges and extending underneath said top and a plate arranged within said block to reinforce and strengthen the same and receive means to fasten said block to its foundation.
- 15 3. A paving or covering block comprising a top having vertical edges, a bottom having vertical edges and provided with alternate flat top flanges and recesses formed on the edges thereof for interlocking engagement with complementary recesses and projections formed on the base edges of adjoining blocks, and a plate arranged within said block and extending substantially the length thereof, and having apertures to receive fasteners for securing said block to a foundation.
- 20 4. A paving or covering block comprising a top having vertical edges, a bottom having vertical edges and shaped to form alternate flat top flanges and recesses entirely around said block for interlocking engagement with complementary recesses and projections formed on the base edges of adjoining blocks, and a plate arranged within said block and extending substantially the length thereof, said plate having apertures aligned with openings in said block to receive fasteners for securing said block to a foundation.
- 25 5. A paving or covering block comprising a top having vertical edges, a bottom having vertical edges and shaped to form alternate flat top flanges and recesses entirely around said block for interlocking engagement with complementary recesses and projections formed on the base edges of adjoining blocks, and a plate embedded in said block inwardly of said recesses and having apertures to receive fasteners for securing said block to a support, said plate extending substantially the length of said block to resist strain and distribute the same.
- 30 6. A paving or covering block, comprising, a rectilinear top, a bottom formed integral with said top and shaped to form on each side of said block a flat top flange extending beyond said top and a complementary recess extending underneath said top, and a reinforcing plate extending substan-

tially the length of said bottom and having apertures to receive fasteners for securing said block to a foundation.

7. A pavement, comprising, a foundation, interlocking paving blocks arranged upon said foundation and having formed on the bases thereof flat top flanges extending beyond the tops of said blocks and complementary recesses extending underneath said tops to receive the flanges of adjoining blocks, and reinforcing plates carried by certain of said blocks and having apertures for receiving fasteners to secure said reinforced blocks to said foundation and hold the adjoining blocks against lateral movement.

8. A pavement, comprising, a foundation, interlocking paving blocks arranged upon said foundation and each comprising a top having vertical edges and a bottom having vertical edges and shaped to form alternate flat top flanges extending beyond said top and recesses extending underneath said top to interlock with the complementary flanges and recesses of adjoining blocks, and reinforcing plates arranged within certain of said blocks and provided with apertures for receiving fasteners to secure said reinforced blocks to said foundation and hold the adjoining blocks against lateral movement.

In witness whereof, I have hereunto subscribed my name.

CLARENCE WRIGHT.

CERTIFICATE OF CORRECTION.

Patent No. 1,778,927.

Granted October 21, 1930, to

CLARENCE WRIGHT.

It is hereby certified that error appears in the printed specification of the above numbered patent requiring correction as follows: Page 2, line 28, claim 3, for "projections" read flanges, and line 31, after the word "thereof" strike out the comma; same page, line 39, claim 4, for "projections" read flanges, and line 43, for ", said plate" read and; line 51, claim 5, for "projections" read flanges; and that the said Letters Patent should be read with these corrections therein that the same may conform to the record of the case in the Patent Office.

Signed and sealed this 1st day of September, A. D. 1931.

(Seal)

M. J. Moore,
Acting Commissioner of Patents.
